COMBINED DISPENSING AND CLOSURE CAP FOR THE NECK OF A CONTAINER

Alvin J. Porter, Excelsior, Minn., assignor to Product
Design & Engineering, Inc., Minneapolis, Minn.

Filed Dec. 31, 1962, Ser. No. 72,998

Term of patent 14 years

(Cl. D58—26)

FIG. 1

FIG. 2

Fig. 3

FIGURE 1 is an elevational view of a combined dispensing and closure cap for the neck of a container embodying my new design.

FIGURE 2 is a top plan view thereof.

FIGURE 3 is a fragmentary top perspective view thereof.

I claim:

The ornamental design for a combined dispensing and closure cap for the neck of a container, as shown.
